UNITED STATES PATENT OFFICE

WILLIAM STEWART BELLHOUSE, OF MANCHESTER, ENGLAND, ASSIGNOR TO THE FINE COTTON SPINNERS & DOUBLERS ASSOCIATION LIMITED, OF MANCHESTER, ENGLAND

WINDING MACHINE

Application filed August 26, 1929, Serial No. 388,537, and in Great Britain November 19, 1928.

The invention relates to yarn or thread winding machines of the type in which a large number of ends of the yarn or thread are wound simultaneously parallel side by side in tape form, flat without twist on to a tube or bobbin at a single operation from which they can be unwound together for lapping on to wire for insulating purposes.

In the winding of yarn or thread in this parallel form on to spools or bobbins, great difficulty has been experienced in retaining the several threads in their flat parallel formation after an end breaks during the operation of winding back from the bobbin and piecing up the broken end.

According to the invention the machine is constructed with a winding back mechanism comprising one or more vertically movable drop fingers fitted to slide on vertical rods to take up the slack of the ends during piecing up and a stop or knock off mechanism applied to every thread to stop the rotation of the winding head on the breakage of any one thread.

25 The invention will be fully described with reference to the accompanying drawings in which a machine is shown capable of winding as many as thirty threads simultaneously on to a spool or bobbin.

30 Fig. 1 is a front elevation of winding frame showing the invention applied thereto.

Fig. 2 is an end elevation.

Fig. 3 is a plan.

35 Fig. 4 is an end elevation of the winding back mechanism.

Fig. 5 is a plan of Fig. 4.

The machine comprises a winding head of known construction of which the winding spindle A is shown, a winding back mechanism B to take up the slack of the threads when unwound from the spool during piecing up, disposed in front of the machine adjacent to the spool or bobbin spindle A, a stop or knock off mechanism D applied to every thread, combs or reeds C to separate the ends as they come from the cones, a vertical creel E at one side of the frame to carry the cones of yarns F and drag guides G therein for each cone to apply a tension separately to each thread. Or instead of a creel E with

cones of yarn F the yarn may be unwound from cops or pirns h on spindle H.

The winding head (not shown) is of known construction with a spool or bobbin spindle A, a driving clutch and a knock off handle a.

55 The winding back mechanism B comprises one or more vertical rods b (preferably three) upon each of which is fitted a vertically movable drop finger b¹ free to move up and down and normally held in position at the top of the rod b by a spring catch b² from which it can be readily released. When winding back to find a broken thread which has run on to the spool at A the parallel threads are drawn back in a bunch and placed beneath one or more of the drop fingers b¹ which are released singly from their catches b² and take up the slack of the threads in zig-zag form without displacing the relative parallel position of the threads. Short horizontal rods b³ are 60 placed between the vertical rods b to support the yarn and between each pair a drop finger carries it down as it is unwound. The rods b³ are fitted into a pivoted frame and are 65 normally turned out of the path of the yarn.

70 The stop mechanism D disposed between the comb or reed C and the winding back mechanism comprises two constantly rotating rollers d, d¹ across which the threads travel and a plurality of looped drop wires d² which are hung one on each thread over the nip of the rollers d, d¹. The roller d is journaled in 75 movable bearings to permit it to move laterally and connected by a rocking lever d³ and wire d⁴ with the knock off handle a. On the falling of any drop wire d² consequent upon the breaking of a thread it is drawn between the rollers d, d¹ displacing the roller d laterally against the locking lever d³ and through the wire d⁴ operates the knock off 80 lever or handle a.

85 The creel E is placed at any convenient position at the side or end of the machine to hold any desired number of cones or bobbins F of yarn, a tension guide device G for each thread and a number of guide pins g at the end to direct the threads to the separating comb or reed C.

90 Instead of or in addition to the creel E 100

spindles H may be placed at the end of the machine to hold cops or pirns h.

What I claim as my invention and desire to protect by Letters Patent is:—

- 5 1. A winding machine constructed with a winding spindle stop mechanism, vertically movable drop fingers, vertical rods upon which the drop fingers slide and spring catches on the vertical rods to normally hold the drop fingers at the top of the rods disposed between the winding spindle and a stop or knock off mechanism by which the slack of the yarn or threads is taken up during the operation of winding back from the spool or bobbin and piecing up the broken end.
- 10 2. In a winding frame a winding back mechanism comprising one or more vertically movable drop fingers fitted to slide on vertical rods and normally held in position at the top of the rods by spring catches.
- 15 3. A winding machine comprising in combination a winding spindle, a stop mechanism, vertically movable drop fingers, vertical rods upon which the drop fingers slide and spring catches on the vertical rods to normally hold the drop fingers at the top of the rods all disposed between the winding head and the stop mechanism.

In testimony whereof I have hereunto set
30 my hand this 16th day of August, 1929.
WILLIAM S. BELLHOUSE.
